United States Patent Office

Des. 177,570
Patented May 1, 1956

177,570

FOOD JAR

George T. James, Pasadena, Calif., assignor to Gladding, McBean & Co., Los Angeles, Calif., a corporation of California

Application July 9, 1954, Serial No. 31,361

Term of patent 14 years

(Cl. D58—25)

Fig. 1.

Fig. 2.

Fig. 3.

Fig. 1 is a plan view of a food jar, showing my new design.

Fig. 2 is a front elevational view thereof; and

Fig. 3 is a side elevational view thereof.

The rear and opposite side of the food jar, not shown, are the same as the front and side illustrated.

I claim:

The ornamental design for a food jar, substantially as shown and described.
